(57) **CLAIM**

The ornamental design for a support stand as shown and described.

DESCRIPTION

FIG. 1 is a rear perspective view of a support stand showing the new design;

FIG. 2 is a front perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a rear perspective view shown in a desk clamp environment; and,

FIG. 10 is a front perspective view of FIG. 9.

Features illustrated in broken or dashed lines form no part of the claimed design.

1 Claim, 10 Drawing Sheets
